J. J. Wright

WITNESS:

UNITED STATES PATENT OFFICE.

VINCE WELESKI, OF TARENTUM, PENNSYLVANIA.

RAIL FASTENER.

Application filed April 12, 1923. Serial No. 631,655.

To all whom it may concern:

Be it known that I, VINCE WELESKI, a citizen of the United States, residing at Tarentum, in the county of Allegheny and State of Pennsylvania, have invented new and useful Improvements in Rail Fasteners, of which the following is a specification.

An object of this invention is to provide a simple, cheap and efficient means for fastening rails on metal ties.

A further object is to produce a fastening means for securing rails on metal ties that comprises two companion members each having a rail flange engaging lip and which are designed to be connected together and secured on a tie by a single bolt.

A further object is to produce a means for fastening rails on metal ties which will prevent the tilting or vertical movement of the ties and retard the creeping of the rails without interfering with the natural longitudinal movement thereof incident to expansion and contraction.

With these objects in view reference is to be had to the drawings which accompany and which form part of this application.

In the drawings:—

Figure 1 is a perspective view showing a rail fastened on a tie in accordance with this invention.

Figure 2 is an end view of the tie with parts broken away and parts in section.

Figure 3 is a perspective view looking toward the notched face of one of the clamping members.

Figure 4 is a similar view looking toward the straight face of the cooperating clamping member.

Again referring to the drawing, the numeral 1 indicates a metal tie provided, adjacent its ends with transverse depressions forming rail seats on the upper face thereof. Only one end of a tie is shown in the drawing, and the rail which has its base flange received in the seat of the said tie is indicated by the numeral 2.

In a line below and centrally with respect to the depression forming the rail seat the tie 1 has a transverse opening 3 therethrough for a bolt member 4 that has its threaded end surrounded by a lock washer 5 and engaged by a nut 6. The bolt passes centrally

through the body portions 7 of my improved rail clamps.

Both clamps are of a similar construction, each including a substantially rectangular body that has one of its faces from its inner end formed with a depression or notch of a depth approximately equaling one-half of the thickness of the body. The notches, of course, form the said face of the body with a shoulder 8, and against this shoulder the reduced end 9 of the cooperating clamp body abuts. The reduced portions of the bodies are, of course, provided with aligning openings for the bolt 3.

The widened outer ends of the bodies 7 are integrally formed at their outer corners with lips 10, the inner faces of the said lips being arranged at an angle to correspond to the angled upper faces of the base flanges of the rail 2. The lips 10 project a suitable distance beyond what I will term the inner face of the clamp bodies and the under flat faces 11 of the projecting portions of the lips rest on the upper face of the tie as clearly disclosed in Figures 1 and 2 of the drawing.

Clamps constructed as above described may be cheaply manufactured and easily applied. As each clamp is of a similar construction a broken or defective clamp may be readily replaced. The clamps, as previously stated, are held associated and are secured on both the rail and tie by a single bolt, and it is thought that the foregoing description, when taken in connection with the drawing will render the construction and advantages of the improvement perfectly clear to those acquainted with the art to which this invention relates.

Having described the invention, I claim:

1. The combination with a metal tie grooved to provide a rail seat and a rail in the seat, of means for clamping the rails on the tie, comprising two companion members having their body portions notched for interengagement and their widened corners formed with rail engaging lips which extend laterally beyond their bodies to rest on the tie, and a single bolt passing through said members and through the tie for securing the same on the tie in rail engagement.

2. The combination with a tie and a rail

resting thereon, of means for clamping the rail on the tie, comprising two companion members each including a flat body portion, having their confronting faces from their outer ends notched for interengagement whereby both faces of the bodies will be flush when associated, both of said bodies having their outer corners formed with rail

engaging lips which extend laterally from the bodies to rest on the tie and to engage 10 the base flanges of the rail, and a bolt passing through the lapping portions of the body and transversely through the tie for securing the clamp on the tie.

In testimony whereof I affix my signature. 15
VINCE WELESKI.
